UNITED STATES PATENT OFFICE.

JOHN N. DUNCAN, OF BOONE, IOWA, ASSIGNOR TO HIMSELF, ARTHUR F. BRAUNBERG,
AND J. C. FLANNERY, ALL OF BOONE, IOWA.

SLEET-HAMMER.

1,380,544.

Specification of Letters Patent. Patented June 7, 1921.

Application filed October 14, 1920. Serial No. 416,883.

To all whom it may concern:

Be it known that I, JOHN N. DUNCAN, a citizen of the United States of America, and resident of Boone, Boone county, Iowa, have 5 invented a new and useful Sleet-Hammer, of which the following is a specification.

The object of this invention is to provide means, adapted to be carried by a trolley, for removing foreign substances such as ice 10 and sleet from a conductor such as a trolley-wire.

A further object of this invention is to provide a pneumatic hammer adapted to be carried by a trolley and arranged to impact 15 with a conductor such as a trolley-wire.

A further object of this invention is to provide means for mounting a pneumatic hammer on a trolley.

A further object of this invention is to 20 provide an improved construction for a pneumatic hammer.

My invention consists in the construction, arrangement and combination of elements hereinafter set forth, pointed out in the 25 claims and illustrated by the accompanying drawing, in which—

Figure 1 is a side elevation showing my device mounted as required for practical use. Fig. 2 is a side elevation, partly in section and on an enlarged scale, showing my device separated from the trolley and conductor. Fig. 3 is a rear elevation and Fig. 4 is a plan of the devices shown in Fig. 2. Figs. 5 and 6 are cross-sections on the indicated lines 5—5 and 6—6 of Fig. 2.

In the construction and mounting of the devices as shown the numeral 10 designates a housing, which is formed with an inclined stem 11 adapted to be received in and supported by the socket of a trolley-harp, of 40 common form. The housing 10 also is formed with a journal bearing 12 adapted to receive and be supported by a journal or pin 13 carried by the harp 12, which pin is identical with the one usually employed to 45 carry a trolley wheel, thus providing means for substituting the housing and devices carried thereby for the trolley wheel. A concaved shoe or contact member 14 is 50 formed on the upper end of the housing 10, above the bearing 12 and is adapted to slide beneath and in contact with a conductor such as a trolley wire 15. The housing 10 is in circuit between the conductor and the motor 55 and controlling means not shown on a car

adapted to carry the harp by means of a rod or pole 16. The housing 10 is formed with a cavity or chamber extending entirely through it on a line substantially parallel with a vertical diameter of the bearing 12, 60 which diameter when extended intersects the shoe 14 substantially midway of its length. The cavity or chamber in the housing 10 is substantially circular in cross-section and of various diameters to accommodate various elements and have various functions. A cylinder 17 is mounted in the cavity or chamber of the housing 10 and at its upper end is fitted to and contacts with an annular portion of the wall of said chamber, while a portion of said cylinder is enlarged in diameter near the opposite end thereof and is threaded and adapted to be screwed into a seat formed in the lower portion of said wall, said seat being of greater 70 diameter than the fitting annular portion above mentioned. A nut 18 is formed on the lower end of the cylinder 17 to facilitate placing and removal thereof. The cavity or chamber in the housing 10 has its greatest 75 diameter surrounding the cylinder 17 between the fitted portion and the threaded seat in its wall, thus forming an air chamber 19, which is in constant communication with the interior of the cylinder and has a like communication at its upper end through ports 20 with the 80 interior of the cylinder and has a like communication at its upper end through ports 21. The cylinder 17 is tubular and the interior diameter thereof is slightly less at its upper end than throughout the major portion 85 of its length. A hammer 22 is fitted within and mounted loosely relative to the cylinder 17, the upper end of the hammer fitting the restricted portion of the bore of the cylinder and also fitting a hole 23 aligning therewith in the top of the housing, said hole forming the upper end of the cavity or chamber in the housing, the lower end portion of said hammer materially less than half its length fitting the larger or body portion of the bore of the cylinder, thus forming or producing an air chamber 24 within the cylinder and surrounding the central portion of the hammer. A plug 25 is 90 screwed into the lower end of the cylinder 17 and abuts the lower end of the hammer 22 and the inner end of the plug closes the bore of the cylinder and constitutes a pressure-head in the operation of the device. The plug 25 extends across the ports 20 in 110

the cylinder and is formed with an annular peripheral groove 26 communicating with said ports and also is formed with radial ports 27 communicating with said groove. 5 The plug 25 also is formed with an axial bore 28 throughout part of its length and communicating at its inner (upper) end with the ports 27, the outer end of said bore being threaded to receive a coupling 29 10 whereby an air hose 30 may be connected to the plug. The hose 30 may be supplied in any desired manner such as by a pump or tank carried on the car above mentioned. When the hammer is at rest, as shown, the 15 upper end thereof is substantially flush with the upper end of the cylinder and the lower end of said hammer is in contact with the upper end of the plug 25. The hammer 22 is formed with a central bore 31 throughout 20 the major portion of its length and opening through the lower end thereof to the pressure-head of the plug 25. Radial ports 32 are formed in the hammer 22 and communicate at times between the bore 31 and the 25 air-chamber 24. The diameter of the cavity or chamber in the housing 10 is enlarged adjacent to the upper end of the cylinder 17, thus forming an exhaust chamber 33, intersected and traversed at times by the 30 hammer 22, and ports 34 are formed in the upper end of the housing and communicate between said chamber and the atmosphere externally of the housing.

When it is desired to remove foreign substances, such as sleet and ice, from the conductor 15, a car equipped as shown and described is run over the line, the shoe 14 taking current from the conductor and the hammer being supplied with compressed air 40 through the hose 30 and its connections. The air enters the housing through the bore 28, ports 27, annular groove 26, and ports 20 and fills the chamber 19 around the cylinder. Air passes from the chamber 19 45 through the ports 21, fills the chamber 24, passes through the ports 32 and bore 31 and expands within the hammer. The action of the compressed air on the pressure-head of the plug 25, reacting on the interior of the hammer and particularly on the head of the bore, forces the hammer outwardly as indicated by dotted lines in Fig. 50 2, into forcible contact or impact with the conductor 15. In its outward movement, 55 the hammer traverses the exhaust chamber 33 and hole 28; the inlet ports 32 of the hammer pass out of register with the cham-

ber 24, thus cutting off the entrance of compressed air to the hammer; and the ports 32 in the hammer come into register with 60 the chamber 33, which is open to the atmosphere through the ports 34, thus permitting relief in the hammer. In its outward movement a shoulder 35 on the hammer traverses the chamber 24 to a point beyond the ports 65 21 and cuts off communication between the chambers 19 and 24 and, further, compresses air and forms a cushion thereof in the upper end portion of the chamber 24. This cushion of air in the upper end portion of 70 the chamber 24 acts as a brake for the outward movement of the hammer and provides reactionary impulse sufficient to return the hammer to its normal position of rest on the pressure head of the plug 25. It will 75 be observed that when the hammer is lifted from the pressure head compressed air may act between the lower end of the hammer and said head directly until the inlet is closed by travel of the ports 32 and thereafter by expansion. Thus the maximum force of the air supply is employed, to move the hammer outwardly and cause it repeatedly to impact or strike the conductor to the end of jarring loose and removing ice and 80 sleet therefrom.

It is to be understood that the hammer may be employed and operated in other work when desired.

I claim as my invention—

1. A sleet hammer comprising a housing removably and replaceably mounted on and adapted to be carried by a trolley harp, means on said housing adapted for electrical contact with a conductor, a pneumatic hammer mounted in said housing and means for applying air within said housing for the operation of said hammer.

2. In a sleet hammer the combination with a trolley and a housing adapted to collect 100 current from a conductor, of a pneumatic hammer carried by said housing and arranged for impact with said conductor.

3. In a sleet hammer, the combination of a housing adapted to be carried by a trolley 105 pole, a shoe on said housing adapted to engage a conductor slidingly and a pneumatic hammer carried by said housing and adapted to impact said conductor.

Signed at Des Moines, in the county of 110 Polk and State of Iowa, this 20th day of September, 1920.

JOHN N. DUNCAN.
